The ornamental design for a display screen with animated graphical user interface, as shown and described.

DESCRIPTION

FIG. 1 is a front view of a first image of a display screen with animated graphical user interface showing our new design; FIG. 2 is a front view of a second image thereof; FIG. 3 is a front view of a third image thereof; FIG. 4 is a front view of a fourth image thereof; FIG. 5 is a front view of a fifth image thereof; FIG. 6 is a front view of a sixth image thereof; FIG. 7 is a front view of a seventh image thereof; and, FIG. 8 is a front view of an eighth image thereof.

The appearance of the animated graphical user interface transitions sequentially between the images shown in FIGS. 1-8. The process or period in which one image transitions to another forms no part of the claimed design.

The dot-dash broken lines showing a display screen and the regular broke lines showing elements of the graphical user interface illustrate portions of the article. None of the broken lines form part of the claimed design.
